SPRAY GUN

George H. Palm, Chicago, Ill., assignor to Illinois
Stamping & Mfg. Co., Chicago, Ill., a corpora-
tion of Illinois

Application January 24, 1948, Serial No. 4,111

10 Claims. (Cl. 299—89)

1
This invention relates to a spray gun, and among its objects are the provision of means whereby the spray gun may be used to spray paints, varnish, lacquer, disinfectant and other liquids, and having an attachment which, when in use, provides means for spraying a foamy cleaning compound upon carpets, rugs, furniture and other articles that are to be cleaned.

Another object is the provision of novel means for containing and supporting the valve mechanism of the spray gun which controls the flow of the liquid from the container to the nozzle.

Another object is the provision of novel means providing an air passage to and around the nozzle, thereby providing an aspirating action on the liquid.

Another object is the provision of a removable and replaceable attachment, whereby a foamy cleaning compound may be sprayed.

Another object is to provide a spray gun having few parts and is simple in construction and operation.

Other objects and advantages will appear in the course of this specification, and with said objects and advantages in view, this invention consists in the several novel features of construction, arrangement and combination of parts hereinafter fully set forth and more particularly defined in the appended claims.

The invention is clearly illustrated in the drawings accompanying this specification, in which:

Fig. 1 is a central vertical longitudinal section through a spray gun embodying a simple form of the present invention;

Fig. 2 is a view partly in plan and partly in horizontal section taken on the line 2—2 of Fig. 1;

Fig. 3 is a horizontal section taken on the line 3—3 of Fig. 1;

Fig. 4 is a central vertical cross section partly broken away taken on the line 4—4 of Fig. 1;

Fig. 5 is a side elevation partly broken away of the spray gun seen in Fig. 1 with the foam spraying attachment secured thereto;

Fig. 6 is a plan of the parts seen in Fig. 5;

Fig. 7 is an enlarged horizontal section partly broken away taken on the line 7—7 of Fig. 5;

Fig. 8 is an end elevation of a foam sprayer shell looking in the direction of the arrows 8, 8 in Fig. 5;

Fig. 9 is a vertical cross section of the attachment taken along the line 9—9 of Fig. 6;

Fig. 10 is an end elevation of a spring clip of the attachment looking in the direction of the arrows 10 in Fig. 6;

Fig. 11 is a fragmental detail view partly in

2
plan and partly in cross section of the spring clip and head showing the parts as they appear before assembly; and

Fig. 12 is a fragmental detail view of the parts seen in Fig. 11 after assembly.

Referring to said drawings and first to Figs. 1 to 4 inclusive, the reference character 15 designates a sprayer head removably secured upon a jar 16 or other container for holding paint, varnish, lacquer, insecticide or other liquids, or for holding a cleaning compound.

The sprayer head comprises an outer shell or cap 17 having parallel side walls 18, a bowed end wall 19 formed with a discharge opening 20, a top wall 21, and a rear wall 22 formed with an air opening 23 around which is secured the end wall 24 of a tubular hose connection 25, from which leads a hose or other flexible tubular member 26 which runs to a source of air under pressure such for instance, the discharge side of a vacuum cleaner (not shown). The hose connection may be secured to the wall 22 of the shell or cap 17 by a flange 27 formed on the wall 22, which surrounds the opening 23 and is spun down 25 upon the wall 24 of the hose connection.

The lower end of the shell or cap 17 is turned outwardly radially as at 28 to overlie the upper end of the jar or container 16 and terminates in an annular downturned flange 29 which surrounds the neck of the jar and is formed with several inwardly struck up threads 30 that threadedly engage with the usual threads on the neck of the jar.

Secured to the lower ends of the walls of the outer shell or cap 17 is an inner shell 31 spaced from the walls of the outer shell or cap to leave air passageways between the two shells, through which air under pressure may flow from the hose connection 25 to and through the discharge opening 20.

The lower portion of the inner shell is cylindrical as at 32, and the upper part of the wall of the inner shell is flattened as at 33 to provide for relatively wide passageways around the inner shell. The upper end of the inner shell is provided with a top wall 34, and the lower end of the inner shell extends outward radially as at 35 to the walls 18, 19 and 22 of the outer shell and is bent downwardly as at 36 to frictionally engage said walls. The lower end of the wall 36 extends outwardly radially as at 37 and contacts the wall 28 of the outer shell. The marginal edge 38 of the wall 37 is circular and flares downward slightly and provides means to retain a washer 39 on the underside of the wall 28 for making

a leak-proof joint with the jar or other container. The two shells 15, 31 may be formed of drawn sheet metal or otherwise as desired.

Secured in the inner shell as by a press fit is a valve seat 40 whose outer cylindrical face conforms to the cylindrical portion 32 of the inner shell. Secured in a bore in the lower end of the valve seat, as by a press fit, is a tube 41 whose lower end terminates slightly above the bottom of the jar. Above the tube, the valve seat is formed with a tapered bore 42 and a disc-like valve 43 normally seats on the wall of the tapered bore. The valve 43 is secured upon the lower end of a valve stem 44 which extends up through a hole in the top wall 34 of the inner shell at which place, the valve stem is non-circular in cross section and moves through a correspondingly shaped opening. To the upper end of the valve stem is threadedly secured a flanged push button 45 which extends out through a hole in the top wall 21 of the outer shell. A coiled compression spring 46 is interposed between the top wall 34 of the inner shell and the lower side of the push button and functions to hold the valve on its seat.

Secured, as by a friction fit, in a nipple 47 formed on an end wall of the inner shell is a discharge nozzle 48 which is arranged in coaxial alignment with the discharge opening 20 in the outer shell. Said discharge nozzle terminates at a point in close proximity to the discharge opening. The discharge nozzle 48 being in exact coaxial alignment with the discharge opening 20, the sprayed liquid will discharge in uniform density.

In use, the jar or other container is filled with the liquid which is to be sprayed upon articles, and the hose connection is connected to a source of air under pressure by the hose or other flexible connection 26. The user may grasp the hose connection in using the spray gun and he depresses the push button, thereby unseating the valve 43 permitting the contents of the jar to be drawn up through the tube 41 by the aspirating action of the air passing around the discharge nozzle 48, the air breaking up the discharging liquid into minute particles and spraying them upon the article to be sprayed. A small orifice 50 in the wall 35 of the inner shell permits air under pressure to enter the jar and thereby facilitate movement of the liquid upward through the tube 41. By releasing the push button, the discharge of the sprayed liquid ceases.

In the form of the invention illustrated in Figs. 5 to 12 inclusive, the sprayer head 15, hose connection 25 and jar 16 illustrated in Figs. 1 to 4 inclusive, may be used. In this form of the invention, a foam sprayer in the nature of an attachment designated generally by the reference character 51 is used.

The attachment comprises, in general, a foam sprayer shell 52 open at both ends and having one enlarged end 53 removably secured on a centrally bored cylindrical head 54 as by several inwardly struck up threads 55 arranged to engage with screw threads 56 formed on the head 54. On one face of the head 54 is formed a flange 56' which is secured in a hole in the base member 57 of a spring clip 58, and projecting from said flange 56' is a tubular member 59, the bore of which is in coaxial alignment with the bore in the head 54. The clip and bored head 54 may be secured together as follows: in the base 57 of the clip is formed a circular hole 65 (see Fig. 10) with several notches 66 radiating therefrom. The flange 56' of the bored head fits in the hole

65, and with suitable dies, the edge portion of the flange 56' is staked at places corresponding to the notches 66, as at 67 and the metal at said places is forced into the notches 65 as at 68 (see Fig. 12). Said tubular member 59 of the bored head 54 fits snugly in the discharge opening 20 of the outer shell of the sprayer head and is held around and in coaxial alignment with the discharge nozzle 48. The inner wall of the tubular member 59 flares outwardly as at 59a to provide an air inlet to the bore of the tubular member. The clip has two arms 60 that project from its base member 57 and normally converge somewhat toward their free ends. The attachment is secured upon the sprayer head 15 by sliding the arms along the side wall of the outer shell of the sprayer head and inserting the tubular member 59 through the opening 20 in the outer shell, the inherent resiliency of the arms serving to firmly grip the sprayer head and hold the attachment thereon.

On the opposite face of the head 54 is formed a tubular member 61 through which the sprayed material discharges into the foam sprayer shell. Between the head 54 and the inturned edge 62 of the foam sprayer shell are several foraminated flanged discs 63, the flanges of which contact with the inner face of the foam sprayer shell and space the discs 63 apart. The flanged discs may be formed of sheet metal punched with suitable dies to provide a multiplicity of apertures in each disc, or, they may be formed of wire mesh, as desired.

In using the spray gun with the attachment, the jar 16 is filled with a suitable liquid cleaning compound and air under pressure is admitted to the sprayer head. By depressing the push button 45, the valve 43 is unseated permitting air under pressure to discharge the cleaning compound through the nozzle 48 where it encounters the several foraminated discs in the foam sprayer shell and is blown through the perforations thereof; it is therefore agitated and broken down into a foamy condition. The discharging air reduces the foam to a spray as it is being discharged from the foam sprayer shell.

Any suitable liquid cleaning compound which can be broken down into a foamy condition may be used. The compound may comprise a soapy solution or it may be composed of chemicals such as are used in the "foam" method of cleaning. A spray gun equipped with the above described attachment may be used to spray a cleaning compound foam upon carpets, rugs, upholstery and many other articles.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. In a spray gun, a sprayer head comprising an outer sheet metal shell having a discharge opening therein, an inner sheet metal shell, there being air passageways between the shells, and a liquid passageway in the inner shell, a discharge nozzle secured to and projecting from the inner shell in coaxial alignment with the discharge opening, said outer shell having an integral lower end formed with a radially extending wall terminating in a cylindrical flange provided with

means to secure the sprayer head upon a container, and the inner shell being formed with a radially extending wall terminating in a downturned wall conforming to and held in frictional contact with the wall of the outer shell, the downturned wall of the inner shell terminating in a radially extending wall contacting with the radial wall of the outer shell and formed with a washer retaining edge portion and a liquid intake tube suspended from said inner shell and operatively connected to the liquid passageway in said inner shell.

2. In a spray gun, a sprayer head comprising an outer shell having a discharge opening therein, and an inner shell, there being air passageways between the shells, and a liquid passageway in the inner shell, a discharge nozzle secured to and projecting from the inner shell in coaxial alignment with the discharge opening, the lower end of the outer shell being formed with a radially extending wall terminating in a cylindrical flange provided with threads to secure the sprayer head upon the threaded neck of a jar, and the inner shell being formed with a radially extending wall terminating in a downturned wall conforming to and held in frictional contact with the wall of the outer shell, the downturned wall of the inner shell terminating in a radially extending wall contacting with the radial wall of the outer shell and formed with a flaring washer retaining edge portion.

3. In a spray gun, a sprayer head comprising an outer sheet metal shell having a hose connection adapted to be connected to a source of compressed air on one wall thereof and a discharge opening in another wall thereof, an inner sheet metal shell, there being air passageways between the shells, a liquid passageway in the inner shell, a discharge nozzle secured to and projecting from the inner shell in axial alignment with the discharge opening in said outer shell, said outer shell having an integral lower end formed with a radially extending wall terminating in a cylindrical flange provided with threads to secure the sprayer head upon the threaded neck of a container, and the inner shell being formed with a radially extending wall terminating in a downturned wall adapted to be press fit within said outer shell whereby said outer and inner shells are maintained in assembled relation, a valve seat press fit into said inner shell to completely enclose the interior thereof, said valve seat having a bore extending therethrough and communicating with the interior of said inner shell, a liquid intake tube press fit into said bore and adapted to extend into the liquid container upon which said sprayer head is mounted, an aperture in the radially extending portion of said inner shell exposing the area over the liquid in the liquid container to air trapped in the air passageway defined by said outer and inner shells, and a movable valve member seated on said valve seat and operable against the normal flow of liquid through said intake means and said bore to admit liquid into the interior of said inner shell.

4. In a spray gun, a sprayer head comprising a hose connection, an outer sheet metal shell having peripheral front, rear and side walls and an inner sheet metal shell including a cylindrical portion secured together and providing a chamber, said outer shell having a lower end formed with a radially extending wall terminating in a cylindrical flange provided with means to secure the sprayer head upon a container, said inner shell also being formed with a radially extending wall

terminating in a slightly flared downturned wall forming a V-shaped annular groove and conforming to and held in frictional contact with the wall of the outer shell, a gasket adapted to be mounted in said V-shaped groove to provide a leakproof joint between the container and the sprayer head, there being air passageways between said shells and the outer shell having a discharge opening in the front wall and an air inlet opening in the rear wall, a bored valve seat secured in said cylindrical portion of said inner shell, a liquid intake tube secured in the bore of the valve seat, a valve adapted to seat on said valve seat, an integral spring urged valve stem projecting out through the top of the inner and outer shell and adapted to control the flow of liquid through said valve seat, a discharge nozzle secured to and projecting from the inner shell in coaxial alignment with the discharge opening in the outer shell, and said hose connection affixed to said outer shell at the air inlet opening.

5. In a spray gun, a sprayer head comprising an outer sheet metal shell having a discharge opening therein, and an inner sheet metal shell, there being air passageways between the shells, and a liquid passageway in the inner shell, a discharge nozzle secured to and projecting from the inner shell in coaxial alignment with the discharge opening, said outer shell having a lower end formed with a radially extending wall terminating in a cylindrical flange provided with means to secure the sprayer head upon a container, and the inner shell being formed with a radially extending wall terminating in a slightly flared downturned wall forming a V-shaped annular groove and conforming to and held in frictional contact with the wall of the outer shell, a gasket adapted to be mounted in said V-shaped groove to provide a leakproof joint between the container and sprayer head, and valve means contained in the inner shell for controlling liquid flow through said discharge nozzle.

6. In a spray gun, a sprayer head comprising an outer sheet metal shell having a discharge opening therein, an inner sheet metal shell, there being air passageways between the shells, a liquid passageway in the inner shell, a discharge nozzle secured to and projecting from the inner shell in coaxial alignment with the discharge opening, said outer shell having an integral lower end formed with a radially extending wall terminating in a cylindrical flange provided with threads to secure the sprayer head upon the threaded neck of a container, and the inner shell being formed with a radially extending wall terminating in a downturned wall adapted to be press fit within said outer shell whereby said outer and inner shells are maintained in assembled relation, a gasket retaining groove formed by a slightly flared downturned edge of the radially extending wall of the inner shell and a contiguous portion of the radially extending wall of the outer shell, and valve means contained in the inner shell for controlling the flow of liquid to said discharge nozzle.

7. In a spray gun, a sprayer head comprising an outer sheet metal shell having a hose connection and a discharge opening, said outer shell provided with an air inlet opening and having also a radially extending wall terminating in a cylindrical flange for attaching the sprayer head to a container, said hose connection affixed to said outer shell about the periphery of the air inlet opening, an inner shell including a hollow cylindrical portion and secured in the sprayer

head, said inner shell also formed with a radially extending wall terminating in a slightly flared downturned wall forming a V-shaped annular gasket retaining groove and conforming to and held in frictional contact with the wall of the outer shell, a discharge nozzle projecting from the hollow cylindrical portion in coaxial alignment with the discharge opening, a valve seat secured in the hollow cylindrical portion of said inner shell and having a bore extending therethrough and communicating with the interior of said inner shell, a liquid intake tube secured within said bore and having the liquid passage-way therein communicating with the bore in said valve seat, a valve adapted to seat on said valve seat for controlling the flow of liquid through said sprayer head, and a valve stem for said valve extending through the top of inner and outer shells in axial alignment with said bore.

8. In a spray gun, a sprayer head comprising an outer shell and an inner shell secured together, said outer shell having a lower end formed with a radially extending wall terminating in a cylindrical flange provided with means to secure the sprayer head upon a container, said inner shell also being formed with a radially extending wall terminating in a slightly flared downturned wall forming a V-shaped annular gasket retaining groove and conforming to and held in frictional contact with the wall of the outer shell, there being air passageways between said shells, the outer shell having an air inlet opening in one wall and a discharge opening in an opposite wall, a discharge nozzle secured to said inner shell in axial alignment with the discharge opening and communicating with the interior of said inner shell, a valve seat having a tapered bore extending therethrough secured in said inner shell, said valve seat closing one side of said inner shell and having the smaller diameter end of said tapered bore spaced adjacent and communicating with the interior of said inner shell, liquid intake means secured to said valve seat and communicating with the bore in said seat, and a spring biased movable valve member seated in the tapered bore in said valve seat and adapted to be moved downwardly toward the greater diameter end of said bore for controlling the flow of liquid into said inner shell.

9. In a spray gun, a sprayer head comprising an outer shell and an inner shell having a hollow cylindrical portion and secured together and defining an air passageway between said shells, the outer shell having an air inlet opening in one wall and a discharge opening in an opposite wall, said outer and inner shells having portions complementally formed whereby the inner shell is mounted within the outer shell and affixed thereto at the complementally formed portions thereof, and also forms an annular V-shaped gasket retaining groove, a discharge nozzle secured to the hollow cylindrical portion of said inner shell in axial alignment with said discharge opening

5 and communicating with the interior of said inner shell, a valve seat frictionally supported within the hollow cylindrical portion of said inner shell and enclosing the interior thereof, said valve seat having a bore extending therethrough and communicating with the interior of said inner shell, liquid intake means connected to said valve seat and communicating with the bore therein, and a movable valve member seated on said valve seat 10 and operable downwardly against the normal flow of liquid through said intake means and said bore to control the flow of liquid therethrough.

10. In a spray gun, a sprayer head comprising an outer shell having a hose connection adapted to be connected to a source of compressed air on one end and a discharge opening in the opposite end, said outer shell also having a cylindrical flange for attaching the sprayer head to a container, an inner shell having a hollow cylindrical portion and secured within said outer shell and having a discharge nozzle secured to the hollow cylindrical portion in axial alignment with the discharge opening in said outer shell, said separate outer and inner shells defining an air passage-way therebetween and having complementally formed portions at the lower ends thereof whereby the outer and inner shells are affixed together and form a V-shaped annular gasket retaining groove, a valve seat frictionally supported within the hollow cylindrical portion of said inner shell and enclosing the interior of the hollow cylindrical portion, said valve seat having a bore extending therethrough and communicating with the interior of said inner shell, liquid intake means connected to said valve seat and communicating with the bore therein, means connecting the air passageway defined between said outer and inner shells to the space over the liquid in the container on which said sprayer head is mounted to facilitate removal of such liquid, and a movable valve member seated on said valve seat and operable against the normal flow of liquid through said intake means and said bore to admit liquid into the interior of said inner shell.

45 GEORGE H. PALM.
